UNITED STATES PATENT OFFICE

2,556,193

VARIABLE-SPEED WIRE SPRAY GUN

Kenneth W. Kenshol, Chicago, Ill., assignor to
Metallizing Company of America, Chicago, Ill.,
a copartnership

Application September 16, 1949, Serial No. 116,200

3 Claims. (Cl. 91—12.2)

1

The present invention relates to a variable speed wire spray gun. This is an apparatus wherein a liquifiable material in wire form is fed at a quickly changeable speed into a chamber where the material is melted, atomized and blown out, issuing in the form of a spray of fine molten particles.

More specifically my invention is concerned with the variable speed feed for the wire, it being an object of my invention to provide a feed of the character described which is sturdy, compact and dependable.

It is another object of my invention to provide a feed of the character described which can be changed rapidly and easily and which maintains high uniformity at all rates of speed.

It is another object of my invention to provide a feed of the character described which has no tendency to kink, bind or jam the wire.

It is another object of my invention to provide a feed of the character described having but few and simple parts and which can be fabricated and assembled at a low cost.

It is another object of my invention to provide a feed of the character described which moves the wire in a straight line at all speeds.

It is another object of my invention to provide a feed of the character described having a short span from the wire entry to the wire exit so that the gun can be made very compact.

It is another object of my invention to provide a feed of the character described which can be readily disassembled for replacement or repair.

It is another object of my invention to provide a feed of the character described which can be manipulated with ease and confidence by comparatively unskilled labor.

Other objects of my invention will in part be obvious and in part will be pointed out herein-after.

My invention accordingly consists in the features of construction, combinations of elements and arrangements of parts which will be exemplified in the device hereinafter described and of which the scope of application will be indicated in the appended claims.

In the accompanying drawings in which is shown one of the various possible embodiments of my invention,

Fig. 1 is a plan view of a wire spray gun having a variable speed wire feed constructed in accordance with my invention;

Fig. 2 is a side view of the gun;

Fig. 3 is a rear view of the wire feed;

Fig. 4 is an enlarged sectional view taken substantially along the line 4—4 of Fig. 2;

2

Fig. 5 is an enlarged sectional view taken substantially along the line 5—5 of Fig. 4; and

Fig. 6 is an enlarged sectional view taken substantially along the line 6—6 of Fig. 3.

Referring now in detail to the drawings, the reference numeral 10 denotes a metal spray gun embodying a variable speed wire feed constructed in accordance with my invention. Said gun includes a conventional spray head 12 having a nozzle 14 and a casing 16 within which is mounted a standard mechanism for liquifying the tip of a fusible wire and a suitable means for sub-dividing the liquified tip into tiny particles which are projected from the gun. The spray head also includes a plurality of inlets 18, 20 and 22 for admitting the usual gases, e. g., acetylene, oxygen and air, which are employed for fusing the tip of the wire and spraying the same. A valve 24 controls the flow of the gases.

10 The gun 10 has an electric motor 26 of standard design serving as a constant speed source of rotary power. Said motor drives a slow speed shaft 28 through a gear reduction 30 of any well known type. The shaft extends through a plate 32 carried by the housing for the gears and its tip is threaded to receive a knurled conical roller 34 which constitutes the driving element for the wire feed means.

20 The wire 36 to be sprayed is guided into the feed means by an entry bushing 38 securely fixed in a side plate 40 extending perpendicular to the plate 32. The wire leaves the feed means and passes into the spray head through a sleeve 42 which is securely fixed in a second side plate 44 running parallel to the plate 40 (see Fig. 5). The two plates 40, 44 are rigidly connected by a tie plate 46 which is perpendicular to the plates 40, 44 and is parallel to the top straight line element of the conical roller 34. These three plates 40, 44, 46 constitute a frame F which is adapted to be mounted for movement in a direction parallel to the aforesaid element at the top of the roller 34. Thus the wire guide and spray head are rigidly interconnected for common movement.

25 The frame mounting means includes a U-shaped bracket 48 whose base is the plate 32 and whose legs comprise truncated, triangular plates 50, 52. The two leg plates 50, 52 are fixed to the stationary base plate 32 and slide on the inner surfaces of the frame plates 40, 44. Each leg plate has a rib 54 on its outer surface, the rib being parallel to said top element of the conical roller. The ribs on the two plates 50, 52 are in registry and are snugly received in keyways 56 on the inner surfaces of the frame side plates 40, 44 whereby said frame is guided for movement rela-

tive to the roller in a direction parallel to said top straight line element.

One of the frame side plates, e. g. the plate 40 includes a slot 58 coextensive with a portion of the associated keyway 56. This slot receives a post 60 which is integral with the underlying rib 54. Said post is transversely tapped to receive a threaded rod 62 on one of whose ends is fixed a shouldered handle 64 and on whose other end is fixed a collar 66. The collar and shoulder ride on opposed edge surfaces of the side plate 40 and thereby prevent axial shifting of the rod. Accordingly, when the rod is turned, the frame F together with the spray head and wire entry guide will be shifted parallel to the top straight line element of the conical feed roller 34. The limits of travel of the frame are determined by abutment of the post 60 against the opposite ends of the slot 58.

To force the wire against the feed roller, a pressure roller 68 is provided having an annular V-shaped wire engaging groove. Said roller is journaled at the center of a pressure lever 70 having its rear end pivotally secured by a pin 72 to the tie plate 46. The forward end of the pressure lever is adjustably secured to the tie plate by a shaft 74. The outer end of said shaft carries a knob 76 and the inner end 78 of the shaft is threaded for reception in a tapped bore 80 formed in the tie plate. The pin 72 and axis of rotation of the roller 68 are parallel to the ribs 54, and said roller is located directly above the top element in the conical feed roller 34. It will be apparent that when the knob 76 is turned in one direction, the pressure roller will move toward the top element of the feed roll and when the knob is reversed, the pressure roller will move in the opposite direction thus enabling different sizes of wire to be accommodated.

The pressure roller is located substantially on the straight line between the bushing 38 and sleeve 42. Because of such construction, the wire 36 moves in a straight line from the entry bushing 38, past the pressure and feed rollers to the exit sleeve 42, regardless of the location of the frame relative to the feed roller. However, as the frame is shifted by turning the handle 64, the wire will be disposed at different portions of the conical feed roller so that it will be fed forwardly at different speeds, the rate of rotation of the feed roller being assumed to be constant.

It thus will be seen that I have provided a variable speed wire spray gun which achieves all the objects of my invention and is well adapted to meet the conditions of practical use.

As various possible embodiments might be made of the above invention, and as various changes might be made in the embodiment above set forth, it is to be understood that all matter herein de-

scribed, or shown in the accompanying drawings, is to be interpreted as illustrative and not in a limiting sense.

Having thus described my invention, I claim as new and desire to secure by Letters Patent:

1. In a variable speed wire spray gun, a stationary frame, a sprayhead having a wire intake rigidly connected thereto, a wire entry guide spaced from the wire intake, a frame connecting the sprayhead rigidly to the wire entry guide with the wire intake aligned with the wire entry guide, a shaft oriented so that a projection of its axis of rotation on an imaginary line extending between the wire intake and the wire entry guide is perpendicular to said line, a conical feed-in roller mounted to turn with said shaft, said imaginary line being tangent to the conical surface of the roller, means to mount said connecting frame on said stationary frame for movement relative thereto in a direction parallel to that straight line element of the conical feed-in roller at which the imaginary line is tangent to the conical surface of the roller, manually manipulative means to shift the connecting frame relative to the stationary frame in said direction, and means movable with the connecting frame to press a wire extending from the wire intake to the wire entry guide against said feed-in roller, said last named means constituting a concave pressure roller mounted on said connecting frame for rotation about an axis parallel to said straight line element and in a plane including said element and the axis of rotation of the shaft for the feed-in roller, the axis of rotation of the concave roller being spaced from said straight line element by a distance equal to the thickness of wire fed into the spray gun plus the radius of the roller.

2. A combination as set forth in claim 1 wherein the mounting for the pressure roller includes a lever rotatably carrying said roller, said lever being mounted on said connecting frame for rotation about an axis parallel to the straight line element of the feed-in roller and spaced from the plane including said straight line element and the axis of rotation of said feed-in roller.

3. A combination as set forth in claim 2 wherein manually manipulative means is provided to move the pressure lever about its axis of rotation with respect to the connecting frame.
